[57] ABSTRACT

A rotary anode for X-ray tubes, wherein the rotary system consisting of the plate, rotor and bearings is connected by springs with the casing of the tube. The invention is particularly characterized in that the plate and the rotor are mounted upon an axle to which a rotary ring of each of two bearings is connected, while the other rotary ring engages a tube provided with springs which provide a connection with the casing and have their own frequency which is substantially less than the driving frequency.

ROTARY ANODE FOR X-RAY TUBES

This invention relates to a rotary anode for X-ray tubes, wherein the rotary system consisting of the plate, the rotor and bearings is connected by springs with the casing of the tube. Spring connections are provided so that the rotary anode should not produce any vibrations or transmit them outwardly.

In a known X-ray tube with a rotary anode at least one of the running rings of the bearings is connected by a disc spring with its corresponding structural part. In a tube of this type there is resiliency in the longitudinal direction of the axle but none in the transverse direction. Thus oscillations of the rotary system are always transmitted to the casing and thus to the cathode in which a glowing wire, namely a glow coil, is located. This coil then begins to swing and strikes its cover representing a Wehnelt cylinder. Weldings can then take place which will make the cathode and thus the tube unuseable.

An object of the present invention is to improve existing constructions of this type.

In the accomplishment of the objectives of the present invention the rotary system is separated from the casing and thus from the cathode with respect to transmission of mechanical vibrations in that the plate and the rotor are mounted upon an axle to which one of the two running rings of the bearings is connected, while the other ring engages a tube provided with springs which constitute a connection with the casing and which have own frequency which is considerably lower than the driving frequency.

In a tube of this type all rotating parts of the tube are mechanically separated from other parts of the tube, since due to the spring parts the amplitude resonance works in the opposite direction, so that there is transmitted only a fraction of the vibration amplitude which approaches zero.

This arrangement prevents in a simple manner that vibrations of the rotor could be transmitted to the cathode with resulting losses in the tube based upon the damage to the cathode. Furthermore outwardly projecting noises are dampened. In addition, any imbalance which can take place is balanced out automatically since the springs permit a new setting of the location of the rotary axle. It is merely necessary to make certain that there is sufficient space for deviations between the rotor and the support, as well as a sufficient resilient path making possible the deviation.

As separating resilient means can be used all elements which can prevent the transmission of vibrations. They can be, as already stated, any springs which are effective between the rotation system and the casing. In a simple but effective construction of the present invention sheet springs are used cut in the tube supporting the bearings. However, other spring devices can be also suitable which make use of the resilient action of spiral springs, etc.

According to an embodiment which is constructionally very easy and which facilitates the making of tubes, the axis of the plate is a central shaft upon which sit the inner rotary rings of the two bearings, while outer rings engage a tube the outer side of which carries the springs. A tube is attached to the casing which constitutes a plug socket into which the tube connected with the bearings is inserted and which is held primarily by the resulting pressure of the springs. To maintain a pre-

determined position indentations, grooves, beads, etc. are provided for the springs. For this construction the rotational system is manufactured separately from the rest of the tube and is inserted into the casing after the other tube parts are finished. In case of a separable casing the rotary system can easily exchanged at any time. An equivalent solution is provided by providing the springs at the inner side of the outer casing.

The invention will appear more clearly from the following detailed description when taken in connection with the accompanying drawing showing by way of example only, preferred embodiments of the inventive idea.

In the drawing:

FIG. 1 is a section through an X-ray tube of the present invention and specifically shows the arrangement of the resilient means at a tube interconnecting the bearings.

FIG. 2 is a partial section through a differently constructed upper bearing wherein the resilient means are arranged at a tube fixed to the casing.

The X-ray tube with rotary anode shown in FIG. 1 has a cylindrical casing 1 and a tube 2 fixed to a front surface of the casing and open to the interior. This tube 2 carries the actual rotary system 3 which includes the two ball bearings 4 and 5. They hold the axle 6 in the middle of the tube 7. This provides the connection of the rotary system 3 through the tube 2 with the casing 1. The rotor 9 consists of copper; its interior is coated by a layer 10 which consists of iron and has a thickness of about 5 mm. The iron can be also applied in the form of a tube. The upper free end of the rotor 9 carries the part 11 of the axle 6 upon which is located the actual rotary anode plate 12 consisting of tungsten.

The X-ray tube is operated in the known manner by actuating voltage applied between the line 13 and the tube 2. By applying a heating voltage of 20 v. between the line 13 and one of the two other lines 14 or 15 the plate 12 is struck by electrons, so that X-rays are produced which can be used in a known manner for making X-ray pictures, etc. Then the plate 12 rotates since from the outside a stator of known design is applied to the casing 1 which produces a rotational moment in the rotor 9 by means of an alternating field. This causes the rotation of the axle 6 which rotates in bearings 4 and 5, the inner rotary rings 16 and 17 of which lie upon the axle 6. The outer rotary rings 18 and 19 engage the tube 7. This tube 7 consists of iron and in annular zones parallel to the bearings 4 and 5 has several outwardly bent tongue-like extensions. There are four of such tongues in each zone in this embodiment. The drawing shows at the upper bearing two tongues 20 and 21 and at the lower bearing two tongues 22 and 23. The insertion of the rotary system 3 is limited by inwardly extending collars 23' which form a snap-in groove for the springs 22, 23 and limit precisely the extent of the insertion. By using spring steel which resists high temperatures as the material for the tube 7, the tongues 20 to 23 receive continuously resilient properties which produce a sufficiently firm hold to resist rotary frequencies developed in X-ray tubes and mechanical loads resulting from supports as well as movements.

The section illustrated in FIG. 2 shows an outer tube 24 which corresponds to the tube 2 of FIG. 1 and which receives the springs. FIG. 2 shows springs 26 and 27 provided close to the bearing 25 which corresponds to the bearing 4. These springs support the inner tube 28

60
65

corresponding to the tube 7. At a location away from the bearing 25 the construction of FIG. 2 has a further series of springs corresponding to the springs 22 and 23 of FIG. 1, so as to provide a sufficiently stable hold. Grooves 29 constitute the fixing means into which snap the springs 26, 27. In this construction similarly to that of FIG. 1, the axle 30 of the anode is separated from the casing by running rings. FIG. 2 shows rings 32 and 32 on the upper bearing 25.

What is claimed is:

1. An X-ray tube with rotary anode, comprising a casing, an anode plate within said casing, a rotor, an axle connected with said plate and said rotor, two spaced bearings, a tube enclosing a part of said axle, each of said bearings having an inner ring carried by said axle and an outer ring connected with said tube, and resilient means connecting said tube with said casing and having own frequency which is substantially lower than the driving frequency.

2. An X-ray tube with rotary anode, according to claim 1, comprising a tube carried by an end of said

casing, the first-mentioned mentioned tube fitting into the second-mentioned tube, and wherein said axle is a central shaft and said resilient means are carried by an outer surface of the first-mentioned tube.

5. An X-ray tube with rotary anode according to claim 2, wherein said resilient means are tongues cut out of the first-mentioned tube.

10. An X-ray tube with rotary anode, comprising a casing, an anode plate with said casing, a rotor, an axle connected with said plate and said rotor, two spaced 15 bearings, a tube enclosing a part of said axle, each of said bearings having an inner ring carried by said axle and an outer ring connected with said tube, another tube enclosing the first-mentioned tube, and resilient means connecting the second-mentioned tube with said casing and having own frequency which is substantially lower than the driving frequency.

15. An X-ray tube with rotary anode according to claim 4, wherein said resilient means are tongues cut out of the second-mentioned tube.
